UNITED STATES PATENT OFFICE.

JOHN F. HENDRICKSON, OF WOLLASTON, MASSACHUSETTS.

COMBINATION-LOCK FOR ELECTRIC CIRCUITS.

1,239,790.

Specification of Letters Patent. Patented Sept. 11, 1917.

Application filed August 9, 1916. Serial No. 113,954.

To all whom it may concern:

Be it known that I, JOHN F. HENDRICKSON, of Wollaston, in the county of Norfolk and State of Massachusetts, have invented 5 certain new and useful Improvements in Combination-Locks for Electric Circuits, of which the following is a specification.

This invention relates to means for preventing the unauthorized use of automobiles 10 and other mechanisms or devices in which a current of electricity is employed, and the chief object of my invention is to provide an improved mechanism which, for convenience of description, I term a lock, said lock having 15 shiftable members which cooperate with correspondingly shiftable members of a removable device which I call a key, so that an electrical circuit may be completed when the key is inserted to operative position, and 20 broken when the key is removed. Since the mechanism includes means for making different combinations that will be known only to the user or owner, it possesses the same advantages in connection with an electric 25 circuit that a combination safe lock does in connection with a receptacle for valuables.

Automobiles employ electric circuits for the spark plugs of the motors, and also for the starting devices. The same is true of 30 motor-boats. With my device in the circuit of an automobile or motor-boat, theft of the machine or boat is rendered difficult. The use of an individual electric motor for each machine in a machine-shop, is the modern 35 idea. Sometimes a machinist wishes to leave a piece of unfinished work in the machine. With my improved device included in the circuit of the motor for that machine, unauthorized or accidental starting of the 40 machine during the absence of the operator from that machine, can be made perplexing and therefore improbable. The device is also useful in connection with the electric light circuit in a house or building to enable 45 the owner, if going away, to interfere with the use of the current during his absence.

My invention consists in the locking or preventing devices substantially as hereinabove described and claimed.

Of the accompanying drawings:

Figure 1 is a diagrammatic view of the parts and some of the circuits as employed on an automobile.

Fig. 2 is a diagrammatic view chiefly to 55 represent the complete circuits.

Fig. 3 is a longitudinal sectional view of the steering post and the portions of my improvements which are carried thereby.

Fig. 4 is a view similar to a portion of 60 Fig. 3 showing the bolt in its locking position.

Fig. 5 represents a section on line 5—5 of Fig. 4.

Fig. 6 is an inner face view of the attachment which is carried by the steering post. 65

Fig. 7 is a plan view of the circuit switch box with its cover open, the dotted lines representing the outer fixed casing from which said switch box is partially withdrawn to either make wiring connections or change the combination. 70

Fig. 8 represents an elevation partly in section of the switch box when in its normal position locked in its outer casing. 75

Fig. 9 represents a section on line 9—9 of Fig. 8.

Fig. 10 represents a section on line 10—10 of Fig. 8, the cover being only partially raised. 80

Fig. 11 is a plan view of the parts below the line 11—11 of Fig. 8.

Figs. 12 and 13 are detail views hereinafter described.

Fig. 14 is a perspective view of one of the 85 duplex removable contact pins of the switch box.

Similar reference characters indicate similar parts in all of the views.

Referring first to Figs. 1 and 2, 20 indicates a support for the devices comprising my invention, which support may be the dash or foot board of an automobile. The tubular post 21 for the tubular steering shaft 22 having the hand wheel 23 extends 90 in the usual inclined direction from said support.

Suitably secured to post 21 is a casing 24 containing the mechanism for controlling the operation of a bolt 25. Said mechanism 100 includes a magnet which, when the key, the knob or head of which is indicated at 27, is inserted in the switch box which is inclosed in another casing 26 also carried by the support 20, will withdraw the bolt 25 from a 105 hole in shaft 22, so that the machine can be steered. Such insertion of the key, as hereinabove described, also establishes a circuit

for the spark plugs of the motor, or the starting device, or both. Fig. 1 is drawn chiefly to show the preferred relative positions of the casings 24 and 26, so that the 5 parts can be conveniently reached by the user of the car.

Mounted in the casing 24 is a magnet 28, preferably, although not necessarily, designed to simultaneously attract two armatures 29 and 31 pivotally supported at 30 and 32 respectively, and pivotally connected together at 33. The armature 29 carries the bolt 25, and the arm of said armature 29 is longer than the arm of armature 31 so that 10 the latter will have less throw than the former, in order that while armature 29 may have ample movement to permit bolt 25 to fully reach a firm locking position as indicated in Figs. 4 and 5, yet armature 31 15 will not move so far away from the magnet as to fail to be operated by it to shift the parts to the position shown in Fig. 3. It is advisable to explain here that the bolt 25 moves from the unlocking position of Fig. 20 3 to the locking position of Figs. 4 and 5 by gravity, although, as is obvious, a spring might be employed to aid gravity. The reason for employing three keeper holes x 25 in shaft 22 is to enable the shaft to be left 30 locked with the steering wheels straight or turned sharply to the right or left. When the combination key hereinafter described is inserted, the magnet 28 is energized and there is a tendency to withdraw the bolt. 35 Mounted to rock in the upper end of casing 24 is a stud shaft 34 having a knob 35 at its outer end and an arm 36 at its inner end. Said arm has a lateral toe 37 and a shoulder 38 at its tip. A spring 39 exerts a constant 40 tendency to hold the arm in the position shown in Fig. 5 bearing against one edge of the armature 29 which has a projection as shown in Fig. 6 for this purpose. When the bolt is in locking position (Fig. 5) the side toe 37 of the arm 36 overlies the edge 45 of the armature and holds the bolt in that position, even when the unlocking magnet 28 is energized, until the user manually operates knob 35 to rock shaft 34 to swing arm 36 so that the toe 37 will release the armature and permit the magnet, when it has been energized, to attract the armature and lift its bolt 25. When the user then releases the knob 35, after the magnet has withdrawn the bolt, the arm 36 returns to the 55 position shown in Fig. 5 but with the side toe 37 below or underlying the armature 29 so as to positively hold the locking bolt 25 raised and in the unlocking position of Fig. 60 3 to avoid any liability of the steering shaft becoming accidentally locked during driving of the car.

As is well known, armatures sometimes become so stuck to magnets as to refuse to leave them when desired, even when the

magnet is not energized. To insure the movement of the armature away from the magnet when the latter is inactive and it is desired that the bolt shall pass to locking position, I provide the arm 36 with a lateral pin 40 (Fig. 5) long enough to act as a cam on the upper surface of armature 29 to push said armature away from the magnet when the arm is swung to the left (Fig. 5) to release the toe 37 from the underlying position above described, said pin 40 thus acting as a manually operated device to push the bolt 25 to, or partially to, the locking position of Fig. 5.

The casing 26 is fixed by any suitable means to the rear surface of the support 20 and, in practice, is preferably so inclosed that the wires hereinafter described will be inaccessible to any person who might seek to short circuit or otherwise tamper with them. Said casing is shown as having an upper cylindrical portion for the switch box presently described, and a lower narrow portion for the circuit wires. The cylindrical portion is in alignment with an opening in the support 20 and the switch box or inner casing 41 is capable of being pulled partly through said opening when a change in the combination of the lock is to be effected.

The switch box 41 has its hinged cover in two sections 42, 43, as indicated in Figs. 7 and 8. As will be hereinafter explained, when the switch box is drawn out of the casing 26 through the opening in the support 20, it can be drawn only to an extent which leaves the section 42 of the cover still extending into the casing 26. This is because the section 42 never needs to be lifted excepting when the parts are to be, or have been, very considerably dismembered, for the purpose of fixing the circuit connections. It is only the cover section 43 that ever needs to be raised for the purpose of changing the combinations within the box.

In the lower portion of the switch box are contained two blocks 44-45 of suitable insulating material, said blocks being so formed or cut away as to provide a space between mid-portions thereof to admit the key and to contain other parts presently described. The space for the key 63, 65, is best indicated in Fig. 9.

Mounted upon the upper block 45 (Fig. 7) are four strips 46, 47, 48, 49 of suitable conducting material; the block 45 being formed with two series of holes 50 between the two pairs of conducting strips as shown in Fig. 7. Said conducting strips extend from suitable supporting studs 51 to four binding posts 52, 53, 54, 55 which are supported by the block 45. Two shiftable or adjustable duplex plugs or contact devices are employed each comprising a pair of pins 56, 57 (Fig. 14) connected to a head 58 of insulating ma-

terial. The upper end of each pin 56, 57 projects outwardly so that when two of the duplex plugs shown in Fig. 14 are fitted in holes 50 as shown in Fig. 7, one of the conducting strips of each pair will be in contact with the upper end of one pin and the other conducting strip of the pair will be in contact with the upper end of the other pin. The conducting strips are resilient so as to be spread slightly apart when the duplex plug is inserted, and then bear yieldingly against the pins 56, 57, to preserve electrical contact.

Referring now chiefly to Fig. 11, slides 59 which may consist of brass tubes, are mounted in ways 60 formed in the upper face of block 44, springs 61 tending to hold the slides 59 in opposition to the thrust of the key hereinafter described. Each slide 59 carries a leaf contact spring 62 which is adapted to slide over and rest against and make electrical contact with the lower portions of the pins 56, 57.

The key or removable member which is to be taken away by the owner or user of the machine or appliance employing the device, when that machine or appliance is to be put out of commission, comprises a shank 63 having the knob or handle 27 hereinbefore mentioned. The shank 63 has a series of holes 64 adapted to hold a pair of pins 65 (Figs. 8 and 11) so as to project from opposite sides of the shank, the pins being removably connected to said shank, as by screw threads or otherwise, so that either pin can be shifted to a different position longitudinally of the shank. The knob or head 27 is rotatably connected with the outer end of the shank 63, and has a cam slot 66 into which a pin 67 projects from the shank (see dotted lines, Figs. 8 and 11) to cause the shank to shift in the direction of its length when the knob is turned as hereinafter described, the pins 65 preventing the shank from turning. The knob or head also has an outwardly projecting pin or detent 68 adapted to be engaged behind a keeper flange 69 which is provided with a notch 70 (Fig. 13) to enable said pin 68 to be inserted behind the keeper flange, said flange serving to keep the key in its operative position after the head has been turned. The space 70 behind the flange 69 forms a socket for the inner end of the knob or head, and for the rotation of the pin 68. After the key is inserted, the knob is slightly turned so as to carry the locking pin 68 aside from the notch 70, thereby locking the key in position. Without this device, or some equivalent therefor, the springs 61 would eject a key because said springs act on the tube slides 59, and the ends of said slides act on the pins of the key. The opposing faces of the insulating blocks 44-45 are cut away or recessed as best indicated in Fig. 9, to guide

the pins of the key and prevent the shank of the key from being rotated after said shank and its pins are inserted.

It may be explained here that, through connections hereinafter described, the electric circuit to be complete must include the duplex plugs, leaf spring contacts 62, slides 51, and the key-shank 63 and its pins 65. When the user or owner wishes to effect a certain combination, he sets the two duplex pins, one of which is shown in Fig. 14, in the desired or preferred holes 50, which holes are indicated by consecutive numerals as shown in Fig. 7, and he correspondingly sets or mounts the two pins 65 of the key so that they will be at the proper distance lengthwise of the shank of the key to effect the pushing of the slides back to accurate position, when the key is inserted to its position of use as indicated in Fig. 11 to complete the circuit just described. If the key is removed and in the pocket of the owner or user who has then gone away, it is difficult for anyone to insert anything that will not only act as a switch from one side to the other of the device but also push the slides to just the proper positions to cause the leaf springs 62 to contact with the pins 56 or 57 to complete a circuit. At least this cannot be effected without much longer expenditure of time than a thief or mischievous person is likely to have time to do.

It is, of course, necessary that the owner or user shall be able to open the lid or cover 43 to make a change of the combination, and it is also desirable that no one else but the possessor of the key, and knowing the proper combination, shall be able to unlock the lid or cover because, if this could be done, it would be quite easy to complete the circuit through the parts inside of the casing. I effect this locking of the cover or lid by the following means:

Mounted upon an insulating plate 73 secured to the inner side of the lid or cover section 43, is a magnet 74 (Figs. 7, 8, 9, 10 and 12) having an armature 75 pivoted at 76 and having a spring 77 which holds said armature against a stop 78 when there is no current through the magnet. Rising from block 45 is a keeper or catch 79 having a beveled side as shown in Fig. 12 so that when the lid is closed the armature will ride down said beveled portion and engage the shoulder of the catch under the influence of the springs 77. This is of course provided that the key is not in position to complete the circuit. Whenever the owner or user inserts the key and the circuit is completed as hereinafter described, the magnet attracts the armature 75 so as to release it from the keeper or catch 79, and enable the user to lift the cover section 43, provided the switch box has been drawn out of the fixed casing 26 far enough to bring said cover section to 130

the front of the support 20; in other words, provided the switch box has been drawn out from its normal operative position, Fig. 8, to the position shown in Fig. 7, to change the lock combination.

To prevent the switch box from being drawn out from the position shown in Fig. 8, excepting by the person having the key with the proper combination, I employ a locking bolt 80 (Figs. 8 and 9) which is adapted to coöperate with a keeper 81 which may comprise a spike or screw driven into the support 20, and having its head in position to coöperate, as a keeper, with said bolt 80. A spring 82, such as a piece of spring wire having one end fitted to an aperture in the bolt 80, and having its other end suitably secured, serves to normally project said bolt 80. The bolt 80 has an enlarged lower end 83 so located as to serve as an armature for one end of the magnet 74. When the magnet 74 is energized, resulting from the insertion and operation of the combination key 63, 65, and the use of an electric current through the circuits hereinafter described, the magnet acts to withdraw the bolt 80 so that the user can then withdraw the switch box from the position shown in Fig. 8, nearly out from the fixed casing 26, so that the cover section 43 can be opened for changing the combination if desired, by shifting the positions of one or both of the duplex plugs 56, 57, 58. In order that the switch box may not be drawn or moved outwardly unless by intention, I provide a suitable catch such as a spring 84 (Fig. 8) secured at one end to the bottom of the switch box and bent to provide a detent shoulder 85, said spring having a knob 86 at its front end. The spring passes through a vertical slot in the support 20, and through a slot 87 in the face plate 88 of the switch box, which face plate is illustrated as carrying the keeper flange 69 hereinbefore described. When the user has inserted the combination key to operative position, and the bolt 80 has been withdrawn by the magnet 74, the switch box still cannot shift outwardly unless the user grasps the knob 86, and lifts it to carry the detent shoulder 85 above the bottom of the slot, and then pulls upon said knob to withdraw the switch box.

Referring to Figs. 7, 8, 10 and 12, I show the insulating block or plate 73 in the cover section 43, as having two blades 89, which are adapted to coöperate, when the said cover section is closed, with two jaws 90, carried by the insulating block 45 of the switch box. A conducting strip 91 connects the binding post 52 with one of the jaws 90 (Fig. 7) and another conducting strip 92 connects the other jaw 90 with an intermediate binding post 93, carried by the insulating block 45. A conducting strip 94 con-

nects the binding posts 54 and 55. These parts just described are diagrammatically illustrated in Fig. 2, in which figure the circuit connections which I will now describe are illustrated:—

A wire 95 connects the magnet 28 with a battery 96 or other source of electricity. A wire 97 connects the battery with the intermediate binding post 93. A wire 98 connects the binding post 54 with the magnet 28. Wires 99 and 100 connect the winding 75 of the magnet 74 with the blades 89. A wire 101 connects the binding post 54 with the spark plugs 102 of the engine of the motor. A wire 103 from said spark plugs is suitably grounded as at 104. A wire 105 connects the binding post 53 with the magnets 106, from which a wire 107 is suitably grounded at 108 by connecting it to any suitable part of the machine.

The above circuits can be followed by comparing Fig. 2 with the other figures which show the details of the different parts of the apparatus. In Fig. 1, which is semi-diagrammatic, I have not attempted to indicate all of the circuits indicated in Fig. 2. In said Fig. 1 there are but three wires shown as issuing from the switchbox which is contained in casing 26. Of these, two of the wires 97 and 98, are supposed to be the same as those similarly indicated in Fig. 2, while the third wire 109 leads to a device 110 which may be either a magneto or the spark plugs of a motor, said device having a wire 111 leading to ground at 112. The said Fig. 1 indicates that I may omit either the magneto or the spark plug connections indicated in Fig. 2. In fact, I may omit other connections so that the use of the combination key will control either the lock device for the steering post alone, or for the magneto alone, or for the spark plugs alone, or for any other mechanism employing an electric current.

In Fig. 8 I have not attempted to indicate which of the several wires there shown are the particular circuit connections above described. It is sufficient to state that those wires which are connected with parts of the switchbox pass through an aperture 113 in the insulation blocks 44 and 45, and through a nipple 114 projecting downwardly from said switchbox and then through a nipple 115 at the bottom of the narrow lower portion of the switchbox casing 26 to the other parts in circuit therewith. Said narrow portion is indicated at 116, and is provided for the purpose of accommodating the portions of the circuit wires so that said portions of the circuit wires can be freely flexed back and forth when the switchbox is shifted out or in.

I will now describe the operation of the mechanism as illustrated:—As has been de-

scribed the head 27 of the key is rotatable on the shank and the shank is capable of moving in and out relatively to the switch box. Since the notch 70 in the keeper flange 5 69 (Fig. 13) is at the top, while the space to permit the insertion of the key shank and its pins is horizontal, said key can only be inserted in a definite manner; that is, the pin 68 of the knob must project upwardly 10 to pass through the notch 70. At this time the pin 67 is at that end of the cam slot 66 which causes the key shank to be projected. When the knob 27 is rotated as far as the 15 flange 69, prevents longitudinal movement of the head while the key shank is retracted or drawn outwardly somewhat due to the action of cam slot 66 on the pin 67. In brief, rotation of the head causes the shank 20 and its contact pins 65 to reciprocate slightly, or move in and out. When the key has been inserted as described and the head rotated, the pin 68 (Fig. 8) passes over the 25 surface of a curved spring strip 117 (see also Fig. 13) which is so shaped that the head 27 will not be accidentally returned to initial position.

If the car has a self starter then the battery 30 96 is to be supposed to be the battery thereof.

When the key is first inserted, its pins 65 engage the slides 59 and push them far enough back so that the leaf springs 62 contact only with the rearmost pins 57 of the 35 duplex plugs as shown in Fig. 2. This results in unlocking the steering wheel, because a circuit is established through wire 95, magnet 28 to act to withdraw bolt 25 as soon as the operator turns knob 35, wire 40 98, post 54, strip 48, the pin 57 of one duplex plug, a spring contact 62 and slide 59 on one side of the key, through the key and the slide 59 and spring contact 62 on the other side of the key, the pin 57 of the other duplex 45 plug, strip 46, post 52, the strip 91, a jaw 90, a blade 89 (since both blades are then in the jaws due to cover 43 being closed), wire 99, magnet 74, wire 100, the other blade 89 and jaw 90, strip 92, post 93, and wire 97 50 to battery. Incidentally the energizing of magnet 74 results in retracting bolt 80 (Fig. 8) and latch armature 75 (Fig. 7) but unless a change is to be made in the combination, or some repairs are to be made, no 55 attention is paid thereto. When, now, the operator rotates the head of the key so as to secure said key in place, such rotation, owing to cam slot 66, results in slightly withdrawing the shank of the key until the 60 spring contacts bear against pins 56 instead of pins 57. This is the position shown in Figs. 2 and 11, and the circuit from the battery is the same as above described until the point 54 is reached, the strip 48 being cut

out. Here the current passes from post 54 65 through strip 94, post 55, strip 49, pin 56, through the key and spring contacts the same as before to strip 47, post 53, wire 105, magneto 106, and to a part of the machine which furnishes the "ground" at 108. From 70 108 the circuit is completed through the metal of the machine including the point 112 (indicated as "ground" in Fig. 1), wire 111, device 110, wire 109, and any part of the mechanism in casing 26 that will complete the circuit through wire 97 back to battery 96. At the same time a current is supplied from post 54, through wire 101 75 to the spark plugs 102 of the motor, through wire 103 to a part of the machine indicated at 104 as "ground," through the metal of the machine to either of the other "ground" connections 108 or 112, through wires and parts of the mechanism in casing 26 to post 80 93, and then wire 97 back to battery 96. 85

Of course the particular wire connections, having nothing to do with the novel features of my invention claimed herein, may be varied to suit the preferences of the electrician installing my locking device. 90

It will be readily understood that the removal of the key results in instant breaking of all circuits, because the springs 61 (Fig. 11) act on slides 59 to carry the leaf spring contacts 62 toward the front of the switch 95 box, away from the pins of the duplex plugs.

Since the circuit through the magnet 74 is broken, the latch armature 75 is acted upon by the spring 77 to engage the catch 79 (Fig. 7) so that it is then impossible for 100 any one, not having the key with the proper combination, to either complete the circuit or unlock or open the lid or cover of the switch box, even if he could pull that switch box out from the fixed casing 26. 105

The device illustrated in the drawings is intended for light circuits such as would not injure the magnets 28 and 74. If the device is made for a heavier current, such as to run the motor of a piece of machinery, 110 then as is obvious, the magnet 74 may be operated by means of shunt wiring. Of course under such circumstances there would be no magnet 28.

I do not limit myself to the specific details of construction illustrated. For instance, the number of different combinations that can be effected may be varied by increasing or decreasing the number of locations for the pins of the duplex plugs, and correspondingly decreasing or increasing the number of possible locations in the shank of the key for the pins 65 thereof. 115

Having now described my invention what I claim is:

1. Means for opposing unauthorized use of a motor vehicle employing electric connections for enabling it to be operated, said 120

- means comprising an adjustable terminal and a removable key having a correspondingly adjustable member for effecting the closing of the circuit through said connections and terminal and through the key.
2. A device for rendering an electric circuit useless, comprising a casing having an aperture, a pair of coöperating but normally separated adjustable contacts within said casing, and a key removable through said aperture, said key having an adjustable member adapted to bring said contacts together by insertion of said key in the casing to effect the completion of the circuit.
3. A device for rendering an electric circuit useless, said device comprising a pair of adjustable terminals and a removable key having a correspondingly adjustable member for effecting the closing of the circuit through the key and through said terminals.
4. Means for preventing completion of an electric circuit, said means having an adjustable terminal member, a contact movable toward and from said terminal member, a manually operable and removable member having a correspondingly adjustable portion adapted to actuate said contact to cause it to engage said terminal member to complete the circuit, and means for automatically shifting said contact away from the terminal member when the said manually operable member is removed.
5. Means for preventing completion of an electric circuit, comprising a pair of terminals and a removable member adapted to complete a circuit which includes said terminals, one of said terminals being adjustable to different operative positions, the removable member having means adjustable to position to accord with the position of said adjustable terminal.
6. A device of the character described, comprising a casing having an opening for a key, and a key movable through said opening, said casing and key having correspondingly adjustable circuit-controlling members relatively positioned to coact when the key is in place.
7. A device of the character described, comprising a casing having an opening for a key, and a key movable through said opening, said casing and key having correspondingly adjustable circuit-controlling members relatively positioned to coact when the key is in place, means being provided for opposing accidental removal of the key when inserted to operative position.
8. A device of the character described, comprising a casing containing a shiftable contact member and having a cover adapted to be opened to permit access for shifting said member, a key having a correspondingly shiftable contact member and adapted to be inserted in and removed from said casing, and means for preventing opening the cover when the key is removed.
9. A device of the character described, comprising a casing containing a shiftable circuit-controlling member and having a cover adapted to be opened to permit access for shifting said member, a key having a correspondingly shiftable circuit-controlling member and adapted to be inserted in and removed from said casing, and means for opposing opening the cover when the key is removed, said means comprising a magnet, an armature, a catch coöperating with said armature, and circuit-connections including said magnet and the shiftable circuit-controlling member in the casing.
10. A device of the character described comprising a casing having a plurality of series of sockets, a contact member for each of said series, said member being adapted to be fitted to any of the sockets, a key adapted to be inserted in and removed from said casing, said key having a plurality of sockets, contact members adapted to engage said sockets of the key, and means for completing a circuit when the key is inserted to predetermined position.
11. A device of the character described, comprising a casing having an opening for a key, a pair of conducting strips having sockets mounted in said casing, pins adapted to be mounted in said sockets, slides movable in said casing and having members to contact with said pins, and a key movable through the opening of the casing and having shiftable means for actuating said slides.
12. A device of the character described comprising a casing having an opening for a key, a pair of conducting strips having sockets mounted in said casing, pins adapted to be mounted in said sockets, slides movable in said casing and having members to contact with said pins, and a key movable through the opening of the casing, said key having a series of sockets, pins adapted to be mounted in adjustable positions in said sockets, and means for securing the key in operative position when inserted.
13. In a device of the character described, two pairs of conducting strips, adjustable conducting pins between said strips, sliding contacts to coöperate with said pins, and a key having adjustable members to actuate said sliding contacts.
14. In a device of the character described, two pairs of conducting strips, adjustable conducting pins between said strips, sliding contacts to coöperate with said pins, and a conducting key having a shank provided with adjustable conducting pins to engage and shift said sliding contacts.
15. In a device of the character described, two pairs of conducting strips, adjustable conducting pins between said strips, sliding

contacts to coöperate with said pins, and a conducting key having a shank provided with adjustable conducting pins to engage and shift said sliding contacts, said key having a head rotatively and slidingly connected with its shank, and means whereby, when the key shank is in place and the head rotated, the shank will shift in the direction of its length.

10 16. In a device of the character described, a pair of conducting strips insulated from

each other, a row of sockets between said strips, a duplex plug having two pins adapted to individually engage said strips, said pins being insulated from each other 15 and adapted to fit said sockets, circuit connections with said strips, and means for selectively controlling a circuit through one or the other of said pins and strips.

In testimony whereof I have affixed my 20 signature.

JOHN F. HENDRICKSON.

Copies of this patent may be obtained for five cents each, by addressing the "Commissioner of Patents, Washington, D. C."
